JOINT SUPPORT AND CONSTRUCTION
MAKING USE THEREOFCarl C. Ahles, Albany, N. Y., assignor to Acme
Steel & Malleable Iron Works, Inc., Buffalo,
N. Y., a corporation of New York

Application May 27, 1933, Serial No. 673,199

12 Claims.

(Cl. 94—18)

While the improvements of the present invention are more particularly useful in connection with pavements and floors, they may also be adapted to sidewalks, bridge floors and to general construction work where joints are necessary.

As regards pavements or floors where slabs of concrete are most often employed, the joints usually contain fillers of suitable material, which in some cases are preformed of a suitable composition and in other cases the material, such as bitumen or the like, is poured into the joints and allowed to set. In some instances the joints extend merely transversely of a pavement, while in other instances they also extend longitudinally with the pavement. The joint openings are of various widths, in cases where a filler is used, so as to endeavor to obtain a continuous wear surface.

Efforts have been made to keep joints in a pavement perfectly sealed so that water will not pass through the joints to the sub-grade, but it has been found more or less difficult to keep the joints so sealed that the sub-grade will not be flooded after a rain. In stretches where the drainage of the sub-grade is poor and where the pavement is subjected to considerable heavy truck travel, one end of each slab is likely to be forced below grade. The front end of each slab facing against the direction of traffic is the end which is subjected to the greatest impact and load, so that this end is slowly forced out of alignment because of the gradual lowering of the surface of the sub-grade or sub-soil by erosion, consolidation or compression, the result being that the front end of the slab may be forced a half an inch or more below grade within a comparatively short time, depending upon the character of the sub-grade, the density of traffic and the drainage conditions.

Also, it is found that the relative positions of adjacent slab ends are often reversed when frost penetrates the sub-grade to any great extent. The rear end of the slab is not very often forced below grade and does not ordinarily require any additional support to keep it at the required elevation, although it is at all times desirable to keep the slabs on each side of a joint in perfect grade in order to prevent cracking and spalling at or near the joints.

Therefore, one of the principal points with which all highway designing engineers are concerned is, with regard to concrete pavements as well as concrete foundations for pavements, to provide joints which are either construction, contraction or expansion joints. Concrete slabs are comparatively strong if built continuously, but the joints break up the continuity, and engineers have endeavored for years to carry the stresses from one side of a joint to the other and still leave the joint free to move in order to take up the expansion and contraction of the pavement due to

moisture, temperature and other changes. Even though reinforced at the ends of each slab to prevent corners and ends from cracking off, it is found that even with pavements of nine to ten inches in thickness, that cracks occur a number of feet back from the end of the slab. These cracks are believed to be caused by the high speed heavily loaded vehicles, which set up stresses and vibrations and cause movement in a slab to such an extent that the sub-grade or sub-soil is displaced and the slab bent down until the crack occurs. These cracks largely occur in the on-coming slab, so that if the joint at the on-coming slab is high, it is hit with a tremendous impact, and if it be low, the load drops onto it with a considerable impact. The pavement once cracked, spalls and disintegrates much more rapidly than the remainder of the pavement to an alarming extent.

Efforts have been made to provide pavements with sheet metal joint supports of considerable area, apparently with the thought of overcoming some of the difficulties, but there are a number of objections to such type of supports. Among these objections it is found that the sheet metal is either so thin that the joint supports formed therefrom are apt to easily corrode and hence lose their supporting strength, or are apt to warp and get out of true, or if they are made of substantial thickness, they are very difficult to handle because of their weight and bulk.

An important object of the present invention is to in part at least overcome the difficulties by providing a metallic joint supporting member which, while it is comparatively light in weight, is very strong and is efficient and durable in use, and is small enough so that one man may conveniently handle it and apply it in its position for use, and he is able to expeditiously place a large number of the improved supports in position.

An important object of the invention and a matter of primary consideration is to have a pavement containing joint supports which are anchored in the adjoining ends of slabs and which are so constructed and arranged that the load can be transmitted across the joints of the pavement, such supports at the same time holding the slabs at each side of the joints at the same uniform grade as constructed, thereby presenting a smooth riding surface and reducing and possibly eliminating all impact at the joint, and also making the supporting power of the pavement practically continuous.

Another object of the present invention is to firmly embed the joint supports in the slabs at each side of the joint, and to construct the supports with protruding supporting portions which extend underneath the adjacent slabs so that the slabs mutually support each other, or to locate the joint supports in the adjacent portion of one

slab so as to extend under the adjacent slab, in all cases leaving the slabs free to move laterally, but still holding the slabs in the same general horizontal plane.

5 Other objects of the invention are to provide simple, efficient and economical joint supports for economical anchorage in an application to slabs where they are separated by joints, whether the joints are to contain fillers or not.

10 These being among the objects of the present invention, the same consists of certain features of construction and combinations of parts to be hereinafter described and then claimed with reference to the accompanying drawings illustrating 15 desirable embodiments of the invention and in which

Fig. 1 is a partial vertical section of a concrete pavement of the usual type provided with the improved joint supports, which are shown in elevation, one of them being in full lines and the other in broken lines;

Fig. 2 is an enlarged view of the joint support in plan;

Fig. 3 is an end elevation thereof as viewed 25 from the left;

Fig. 4 is a cross-section on the line 4—4, Fig. 3;

Fig. 5 is a cross-section of a portion of a pavement showing a modified form of joint support in elevation;

30 Fig. 6 is a cross-section of such modified support on line 6—6, Fig. 5;

Fig. 7 is a diagrammatic plan illustrating a number of slabs provided with the improved joint supports of Fig. 1, and

35 Fig. 8 is a plan view partly broken away to illustrate how the improved joint supports may be used on the outer edges of the slabs to hold them against going out of lateral alignment edge-wise of the pavement.

40 Referring to Figs. 2, 3 and 4, the preferred construction of improved joint support includes a bar or rod 10, an abutment member 11 and a supporting member 12. Bar 10 is shown as straight and elongated and forms an anchoring member. 45 Abutment member 11 extends perpendicularly to one end of the bar 10, while supporting member 12 is in the form of a blade extending perpendicularly to the abutment member. The side edges 50 13 of the abutment member are inclined towards each other from the supporting member 12 to the bar 10 so as to taper it gradually and to distribute the metal properly without unnecessary excess.

55 It may be found desirable to round off at 14, 15, respectively, the back surfaces of the abutment member 11 and the supporting member 12 so as to thicken them and to provide reinforcement for the joint support. The back surfaces referred to are those surfaces which are outside of the inner angle formed between the abutment 60 member 11 and the supporting member 12. A strengthening web 16 may be found desirable to reinforce the inner angle between the bar 10 and the abutment member 11, as shown in Fig. 1. A similar strengthening web may, if found desirable, be provided in the inner angle formed between the abutment member 11 and the supporting member 12. The bar 10 is terminated 65 preferably by a lateral enlargement or head 17 to resist longitudinal movement of the joint support when it is in use.

70 Each joint support is preferably cast or forged in one piece, although it may be found desirable to form the support of two or more separate pieces, to be later joined by proper mechanical means; or to form the same of sheet metal prop-

erly designed, formed and shaped to provide elements corresponding in function and advantages to those of a cast or forged joint support. The proportions of the parts may be such that the overall length of the bar 10, plus the thickness of member 11, is approximately nine inches, the bar having an approximate diameter of three quarters of an inch. The dimensions of the blade in both directions thereof may each be three inches, and from the outer side of the bar 10 to the inner surface of the supporting member 12 may be four inches. Preferably the adjacent inner surfaces of the abutment member 11 and the supporting member 12 are flat. Of course the dimensions of the parts may be varied according to requirements.

75 In Fig. 1 the improved joint supports are shown in connection with parts of construction work, as, for example, a pavement of a highway. The sub-soil or bed 18 may be such as is afforded naturally or as in some cases it may be formed artificially. Slabs 19, 20 usually of concrete rest upon the sub-soil or bed 18 and provide the wear surface of the pavement. These slabs vary in dimensions in various sections of the country 25 and usually extend transversely of the highway so as to provide transverse joints 21 while sometimes the pavement is also provided with longitudinal joints. The present invention is more particularly adapted for use in connection with 30 joints 21, especially where the slabs are spaced apart for receiving a filler 22. The filler 22 may be composed of bitumen or other filling material poured into the joint and allowed to set thereafter, or the filler may be preformed. Such 35 fillers allow the joint to expand and contract due to varying conditions.

40 The preferred manner of constructing a pavement according to the present invention is diagrammatically illustrated in Fig. 7 where portions of two slabs 19 are shown as adjoining a slab 20 which is broken away lengthwise on account of the varying lengths of the slabs in proportion to the width of the pavement across the highway. The reference numerals are the 45 same as applied to the previously described figures in so far as numerals are necessary, except that as Fig. 7 is a plan of the improved pavement, it shows the improved joint supports 23 extending at suitable intervals apart along the joints 50 and at the adjacent portions of the slabs. The supports 23 are preferably arranged in more or less evenly staggered relation, as shown. The joint supports may also be arranged in pairs, quite close together or abutting in each pair. In 55 Fig. 1 two joint supports are illustrated, one of them being in full lines and the other in broken lines, as it is offset from the former laterally.

60 It is obvious from Figs. 1 and 7 how the improved joint supports are applied to a concrete pavement. The slabs of the pavement may be formed in the usual manner, after the supports which are to be arranged along each joint have been positioned to that of their ultimate position.

65 It will be seen that the ultimate position of the joint supports is such that the bars 10 extend in opposite direction from opposite sides of a joint, for a considerable distance into the slabs 19, 20, so that when the concrete has set, the said bars are solidly anchored in the slabs. The 70 abutment member 11 is shown extending downwardly from the bar 10 so that its preferably flat inner surface coincides with the corresponding surface of the slab in which the support is anchored, although the exact coincidence of these 75

surfaces is not necessary. The abutment member 11 is shown extending to the bottom of the joint and the blade-like supporting member 12 extends across the joint and for a considerable distance directly underneath the bottom of said slab 19. Hence it will be seen that the supporting member 12 is embedded for a suitable distance in the sub-grade or sub-bed and that it supports the adjacent end of the slab 19, although this supporting member 12 may be partly or wholly embedded in the concrete of slab 19. It is assumed that the direction of traffic is across the joint 21 and towards the slab 20, as in such case the slab 20 is the one which is apt to deviate from the desired perfect grade, and it will also be seen that as the slab 19 rests at the adjacent end upon the supporting member 12, it resists any tendency of the slab 20 to move upwardly, while on the other hand, when 0 if a companion joint support of a pair is embedded in the concrete slab 19, its supporting member 12 will act to support the adjacent end of the slab 20 so that it will not move downwardly. If the traffic be only in one direction it may not 5 be found necessary to use paired-joint supports, but as on most highways the traffic is in both directions, it is very desirable that the joint supports be paired so that the slabs at opposite sides of a joint 21 will act to mutually support 10 each other. When the pavement is subjected to expansion or contraction it will be clear that the ends of each slab are slidingly supported by the supporting member 12. The fillers 22 are placed in position in the joints in the usual way and 15 each filler will abut the member 11.

The construction and design of the improved joint support may be modified depending upon its spacing, the thickness of the slab, the nature of the sub-grade or foundation bed and the load 20 expected to be carried. It will be seen that the improved joint supports, especially when embedded in the pavement in pairs, or the equivalent thereof, tend to keep the slab on each side of the joint at grade and to prevent cracking and 25 spalling at or near the joints, whether or not the adjacent ends of the slabs are reinforced.

These improved joint supports are so constructed, designed and proportioned, that they may be conveniently and expeditiously handled 30 and applied by the workmen on the job, thereby not only facilitating the construction work, but providing with a relatively minimum amount of metal, great strength, durability and great reliability in a pavement of a highway in particular which may be equipped with the improved 35 joint supports.

Referring to Figs. 5 and 6, slabs of concrete pavement are illustrated which are supported by a modified construction of joint support. Here 40 the anchoring bar 24 is of a length somewhat greater than the length of two anchoring pairs 10; that is to say it is a bar long enough to be embedded in adjacent portions of two slabs and to extend across the joint. There is formed in 45 one piece therewith an abutment member 25 at the approximate mid-length of the bar 24, which extends downwardly to the bottom of the joint and is there terminated by oppositely extending 50 blade-like supporting members 26, 27. As the parts are all preferably formed in one piece, a two-way joint support is provided without the necessity of using two separate joint supports, inasmuch as the opposite end portions of the bar 24 will be firmly embedded in the concrete and 55 the supporting members 26, 27 will extend un-

derneath and support the adjacent ends of the slabs.

In Fig. 8 the improved joint supports are shown as useful in another respect than hereinbefore described. Here it will be seen that the 5 slabs 28, 29 are separated by an expansion joint filler 30, but the joint support as hereinbefore described is turned through an angle of ninety degrees; that is to say, although the anchoring bars 10 are embedded in slab 28 in the usual 10 way, the members 11, 12 extend laterally of the bar towards opposite sides of the pavement of the highway, so that the blade-like supporting members 12 fit against the outside edges of the slab instead of upon the bottom of the slab. 15 When the joint supports are applied in this manner, they prevent individual slabs from moving laterally out of alignment, or the shifting of a slab which often occurs on slippery clay sub-soil or on side hills where settlement occurs 20 and causes a dangerous and unsightly condition.

From the description and illustrations it is obvious that the present invention is directed towards an advance in the art, and that the invention is susceptible to modifications other 25 than described and shown, without departing from the scope of the appended claims.

What I claim as new is,—

1. A metallic joint support, including an anchoring member and a bracket at one end of the 30 anchoring member, having a supporting blade and an abutment member extending perpendicularly to the plane of the blade and to the anchoring member and connecting the two, and the anchoring member and blade extending in 35 generally opposite directions from the abutment member, the abutment member gradually tapering off at its opposite edges towards the anchoring member and the greatest width of the abutment member being where it joins with the supporting blade.

2. A joint support, formed from one piece of metal, and including an anchoring member and a bracket at one end of the anchoring member, having a supporting blade and an abutment 45 member extending substantially perpendicularly to the plane of the blade and to the anchoring member, the anchoring member and blade extending in generally opposite directions from the abutment member, and the blade extending laterally away from opposite sides of the anchoring member, the blade and abutment member being reinforced and thickened substantially 50 throughout across the backs thereof by transversely raised portions and the reinforcement 55 extending around the outer corner formed by the abutment member and blade.

3. A joint support, formed from one piece of metal, and including an anchoring member and a bracket at one end of the anchoring member, 60 having a supporting blade and an abutment member extending substantially perpendicularly to the plane of the blade and to the anchoring member, the anchoring member and blade extending in generally opposite directions from the abutment member, and the blade extending laterally away from opposite sides of the anchoring member, and a strengthening web in the inner corner formed between the anchoring member and the abutment member and connecting 65 the anchoring member and abutment member.

4. A joint support, formed from one piece of metal, and including an anchoring member and a bracket at one end of the anchoring member, 70 having a supporting blade and an abutment 75 member extending substantially perpendicularly to the plane of the blade and to the anchoring member, the anchoring member and blade extending laterally away from opposite sides of the anchoring member, and a strengthening web in the inner corner formed between the anchoring member and the abutment member.

- member extending substantially perpendicularly to the plane of the blade and to the anchoring member, the anchoring member and blade extending in generally opposite directions from the abutment member, and the blade extending laterally away from opposite sides of the anchoring member, and means projecting laterally from the anchoring member for embedment with the anchoring member in the concrete of the road and resisting longitudinal movement of the anchoring member when the support is in use.
5. A metallic joint support, including an anchoring bar, rigid means on the bar and extending perpendicularly from its middle portion, and a pair of supporting members offset from the bar and extending in opposite directions from the rigid means.
6. The combination with a plurality of concrete slabs arranged edge opposite edge to provide a pavement or floor having a joint between the edges, of supporting bars embedded in the adjoining slabs and each provided with depending rigid means, and a pair of supporting members extending in opposite directions from the rigid means in supporting relation to the adjoining slabs.
7. The combination with a plurality of concrete slabs arranged to provide a pavement or the like having joints between the edges, of supporting bars embedded in the concrete of each slab at one side of a joint, each bar having a downward abutment member at such joint and each abutment member having at its lower end a supporting blade which extends away from it in opposite direction to the bar and across such joint in direct supporting relation to the slab at the opposite side of the joint, the blade also extending laterally away from opposite sides of the bar, each bar with its abutment member and blade formed from a single casting, and the abutment member gradually tapering off at its side edges up toward the bar so that the greatest width of the abutment member is where it joins with the blade across the width of the blade.
8. The combination with a plurality of concrete slabs arranged to provide a pavement or the like having joints between the edges, of supporting bars embedded in the concrete of each slab at one side of a joint, each bar having a downward abutment member at such joint and each abutment member having at its lower end a supporting blade which extends away from it in opposite direction to the bar and across such joint in direct supporting relation to the slab at the opposite side of the joint, the blade also extending laterally away from opposite sides of the bar, each bar with its abutment member and blade formed from a single casting, the blade and abutment member of each bar being reinforced and thickened substantially throughout, across the backs thereof, by transversely raised portions, and the reinforcement extending around the outer corner formed by each abutment member and the blade.
9. The combination with a plurality of concrete slabs arranged to provide a pavement or the like having joints between the edges, of supporting bars embedded in the concrete of each slab at one side of a joint, each bar having a downward abutment member at such joint and each abutment member having at its lower end a supporting blade which extends away from it in opposite direction to the bar and across such joint in direct supporting relation to the slab at the opposite side of the joint, the blade also extending laterally away from opposite sides of the bar, each bar with its abutment member and blade formed from a single casting, and a strengthening web occupying the inner corner formed between each supporting bar and its abutment member and connecting the bar and the abutment member.
10. The combination with a plurality of concrete slabs arranged to provide a pavement or the like having joints between the edges, of supporting bars embedded in the concrete of each slab at one side of a joint, each bar having a downward abutment member at such joint and each abutment member having at its lower end a supporting blade which extends away from it in opposite direction to the bar and across such joint in direct supporting relation to the slab at the opposite side of the joint, the blade also extending laterally away from opposite sides of the bar, each bar with its abutment member and blade formed from a single casting, and means projecting laterally from each bar and embedded with the bar in the concrete to resist longitudinal movement of the bar, the abutment member and blade thereon.
11. The combination with a plurality of concrete slabs arranged to provide a pavement or the like having joints between the edges, of supporting bars embedded in the concrete of each slab at one side of a joint, each bar having a downward abutment member at such joint and each abutment member having at its lower end a supporting blade which extends away from it in opposite direction to the bar and across such joint in direct supporting relation to the slab at the opposite side of the joint, the blade also extending laterally away from opposite sides of the bar, each bar with its abutment member and blade formed from a single casting, the abutment member gradually tapering off at its side edges up toward the bar so that the greatest width of the abutment member is where it joins with the blade across the width of the blade and a strengthening web occupying the inner corner formed between each supporting bar and its abutment member and connecting the bar and the abutment member.
12. The combination with a plurality of concrete slabs arranged to provide a pavement or the like having joints between the edges, of supporting bars embedded in the concrete of each slab at one side of a joint, each bar having a downward abutment member at such joint and each abutment member having at its lower end a supporting blade which extends away from it in opposite direction to the bar and across such joint in direct supporting relation to the slab at the opposite side of the joint, the blade also extending laterally away from opposite sides of the bar, each bar with its abutment member and blade formed from a single casting, the abutment member gradually tapering off at its side edges up toward the bar so that the greatest width of the abutment member is where it joins with the blade across the width of the blade and a strengthening web occupying the inner corner formed between each supporting bar and its abutment member and connecting the bar and the abutment member, and the blade and abutment member of each bar being reinforced and thickened substantially throughout, across the backs thereof, by transversely raised portions, and the reinforcement extending around the outer corner formed by each abutment member and the blade.
